PERCUSSION MUSICAL INSTRUMENT

Charles Hultsch, Elkhart, Ind., assignor to C. G. Conn, Ltd., Elkhart, Ind., a corporation of Indiana

Application September 6, 1934, Serial No. 742,894

6 Claims. (Cl. 84—403)

My invention relates to percussion musical instruments of the xylophone type, commonly referred to as marimba-xylophones, i. e. instruments having rigid-bar vibrators arranged generally 5 in the manner of a piano keyboard.

The principal object of this invention is to provide a percussion musical instrument in which each tone bar is a dual tone bar unit composed of a pair of tone bars, one of which is an octave 10 lower than the other, and each of which units is preferably of substantially the same horizontal dimensions as the single bar as heretofore used, so that the instrument can be played the same as a standard instrument but with each tone doubled 15 an octave higher, thus giving a greatly enriched tone.

Another object of the invention is to provide a percussion musical instrument in which each tone bar is a dual unit with a resonator for each bar 20 of the two bars of the dual unit, and in which one of the bars of the dual unit is pitched an octave lower than the second bar.

A third object is to provide a percussion musical instrument having two rows of tone bars to effect 25 the chromatic scale, and wherein each tone bar is a dual unit composed of two spaced tone bars, one of which is an octave lower than the other.

Another object of the invention is to provide a percussion musical instrument having two rows 30 of dual tone bars to effect the chromatic scale, each dual tone bar being composed of two bars pitched in different octaves, and wherein each dual tone bar has a pair of different sized resonators associated therewith. Preferably the 35 larger resonator is mounted to cooperate with both bars, and the smaller one cooperates only with the bar of higher pitch.

And yet another object of the invention is to provide a percussion musical instrument in which 40 each tone bar is a dual unit composed of two separate spaced bars which are pitched an octave apart, and wherein two resonators of different sizes are associated with each dual tone bar unit, the smaller of said resonators being substantially 45 the same size, or area, as the larger of the two resonators for the dual tone bar unit positioned in the instrument one octave higher up on the scale.

In attaining the foregoing objects the two parts 50 of each bar or unit are preferably made of the same size and shape in their horizontal dimensions, the octave difference in pitch being secured by making one bar of each pair thicker than the other. This permits the playing of the instrument by anyone skilled on a standard instrument, 55 for example by double-headed mallets for striking

the two parts independently and simultaneously.

This construction, and other structural features and novel arrangements useful in securing the desired effects, will be apparent from the following description of the illustrative embodiment shown 5 in the accompanying drawing, in which:

Figure 1 illustrates a perspective view of a percussion musical instrument in which my invention is incorporated;

Figure 2 is a top plan view of the instrument 10 showing some of the tone bar units broken away to disclose the resonator;

Figure 3 is a section taken on line 3—3 of Fig. 2; and

Figure 4 illustrates a fragment of a mallet for 15 playing the instrument illustrated in Figures 1 and 2.

Similar numerals of reference indicate like parts throughout the several views on the drawing.

Referring now to the details of the drawing the letter A indicates generally a supporting frame which may include the end bars 1 and 2 suitably secured to the frame side bars 3 and 4 to provide a rigid structure, and which may include also the 25 two intermediate longitudinal frame bars 5 and 6 rigidly secured at their opposite ends to the frame end bars 1 and 2, the whole to support the tone bars and resonators of this musical instrument, as herein described.

The frame A, thus generally described, may be carried on a sub-structure B which may be provided with suitable legs. The frame A may include also the two end bars 7 and 8 rigidly connected with the end bars 1 and 2 in any suitable 35 manner and which may be pivotally mounted at 9 in the sub-frame B, said mount forming no part of this invention.

My improved percussion musical instrument may comprise two rows of dual tone bar units, of 40 which the front row is indicated generally by the letter C and the rear row by the letter D, the latter of which may be elevated somewhat above the former, the two rows thus arranged being adapted to produce the chromatic scale. Each of the rows 45 C and D comprises a plurality of dual tone bar units, or sets, each unit, or set, comprising a left hand tone bar 10 and a right hand tone bar 11 mounted adjacent and parallel with each other upon suitable brackets 12, 12, the latter being carried by the frame side bars 3, 4, 5 and 6. Inasmuch as all of the several sets of dual tone bar units are of similar construction it is believed that a description of one set thereof will suffice.

Accordingly, the two bars 10 and 11 may be 55

made of any suitable material, preferably wood, and may be made one half the width usually employed for a similar musical instrument of the same size, each left hand bar 10 being cut away at 5 13 on the underside thereof to pitch the tone thereof one octave lower than the tone produced by the bar 11 of said unit. Each dual tone unit, or set, which is composed of the two spaced parallel tone bars 10 and 11, as described, has associated therewith a pair of tubular depending resonators 14 and 15, respectively, which resonators are arranged in series beneath and longitudinally of each dual unit intermediate the extremities thereof, and in which arrangement and 10 combination the resonator 14 is associated with the bar 10, and resonator 15 with tone bar 11, the resonator 14 being larger or of greater area than the resonator 15. The larger resonator 14 is arranged below both bars 10 and 11, and responds to 15 both of them, whereas the smaller resonator 15 is arranged below and responds mainly to the higher pitched bar 11.

It will be evident from the foregoing that there are two rows of resonators for each row of tone 20 bar units, or sets, the resonators 14 being arranged in one row and resonators 15 in a separate adjacent row. The two series of resonators 14 may be carried by a pair of spaced carrier bars 16 and 17 mounted in the frame end bars 1 and 2, 25 and to and between which carrier bars said resonators may be secured in any suitable manner. And the two series of resonators 15 may be carried by a pair of spaced carrier bars 18 and 19 mounted in the frame end bars 1 and 2 in any suitable manner, between which bars said resonators may be 30 secured in any suitable manner.

All of the resonators 14 and 15 may be the conventional tubular metal type having a closed lower end, and necessarily, both rows of the resonators 14 and 15 vary in diameter and length in the extension thereof up the scale of the instrument. And in this arrangement and construction of the resonators, any one of the smaller resonators 15 is substantially the same size, or area, as the 35 larger of the two resonators for the dual tone bar unit which is positioned one octave higher up on the scale.

The mallet used for playing my improved musical instrument is indicated by the numeral 20 50 at Fig. 4 and it is provided with a pair of spaced heads 21 with which both tone bars 10 and 11, of any of the several dual tone bar units, or sets, are adapted to be simultaneously struck. The combined tones of any two of the bars 10 and 11 55 is richly harmonious, especially enriching the tone quality of the lower pitched bar 10 by thus adding the octave above the note produced thereby.

I am aware that details of construction may be 60 varied through a wide range without departing from the principle of my invention, and I therefore do not purpose limiting the patent granted otherwise than necessitated by any prior art.

I claim:

65 1. In a percussion musical instrument of the xylophone type, the combination of a plurality of dual tone bar units arranged in sequence and constituting one or more octaves, the two bars of each dual tone bar unit being adapted to be 70 simultaneously struck by a single mallet, one of the bars of each dual tone bar unit being pitched one octave below the other bar thereof, and resonators mounted below said sequence of tone bar units, one of the resonators associated with 75 each unit being larger than the other and being

arranged below both bars of the unit and the smaller one being located below the higher-pitched bar of the unit.

2. A percussion musical instrument of the xylophone type comprising tone bar units each having approximately the same horizontal dimensions as the corresponding single tone bar of a standard instrument as heretofore used, and each comprising two bars arranged closely beside each other and which are of different dimensions such that one is pitched an octave above the other, the units being arranged in a series such that the bars on one side of successive units form a scale and the bars on the other side form the same scale an octave higher than the first scale. 15

3. A percussion musical instrument of the xylophone type comprising tone bar units each having approximately the same horizontal dimensions as the corresponding single tone bar of a standard instrument as heretofore used, and each unit comprising two bars arranged closely beside each other and which are the same in their horizontal dimensions but which are of different thicknesses such that one is pitched an octave above the other, the units being arranged in a series such that the bars on one side of successive units form a scale and the bars on the other side form the same scale an octave higher than the first scale. 25

4. A percussion musical instrument of the xylophone type comprising tone bar units each having approximately the same horizontal dimensions as the corresponding single tone bar of a standard instrument as heretofore used, and each unit comprising two bars arranged closely beside each other and which are the same in their horizontal dimensions but which are of different thicknesses such that one is pitched an octave above the other, the units being arranged in a series such that the bars on one side of successive units form a scale and the bars on the other side form the same scale an octave higher than the first scale, together with resonators for the various bars, the resonator of the higher-pitched bar of each unit being the same as the resonator of the lower-pitched bar of the unit an octave higher on the instrument. 35

5. A percussion musical instrument of the xylophone type comprising tone bar units each consisting of two bars arranged closely beside each other and which are the same in their horizontal dimensions but which are of different thicknesses such that one is pitched an octave above the other, the units being arranged in a series such that the bars on one side of successive units form a scale and the bars on the other side form the same scale an octave higher than the first scale, together with resonators for the various bars, the resonators for the lower pitched bars of the units being arranged in one series relative to the lengths of the bars and below the two bars of the respective units and the resonators for the higher pitched bars of the units being arranged in another series differently arranged relative to the lengths of the bars and below the higher-pitched bars of the respective units. 55

6. A unit for a xylophone or the like comprising a pair of adjacent and parallel tone bars having the same horizontal dimensions and differing in thickness so that one is pitched an octave above the other, in combination with a large resonator below both bars and a smaller resonator below the higher-pitched bar. 70

CHARLES HULTSCH.
